United States Patent Office

Des. 224,760
Patented Sept. 12, 1972

224,760

CIGARETTE HOLDER

Milton P. Chernack, West Hempstead, N.Y., assignor to Delcron Products, Inc., New York, N.Y.

Filed Dec. 14, 1970, Ser. No. 26,466

Term of patent 14 years

Int. Cl. D27—02

U.S. Cl. D85—8

Fig. 1.

Fig. 2.

Fig. 3.

Fig. 4.

Fig. 5.

Fig. 6.

Fig. 7.

FIG. 1 is a front perspective view of a cigarette holder showing my new design;

FIG. 2 is a rear perspective of FIG. 1;

FIG. 3 is a top plan view of FIG. 1;

FIG. 4 is a side elevational view thereof;

FIG. 5 is a bottom plan view thereof;

FIG. 6 is a front end elevational view thereof; and

FIG. 7 is a rear end elevational view thereof.

I claim:

The ornamental design for a cigarette holder, as shown.
